UNITED STATES PATENT OFFICE

LOUIS A. SUEKOFF, OF WILMETTE, ILLINOIS

SPRING ASSEMBLY FOR MATTRESSES OR CUSHIONS

Application filed July 26, 1930. Serial No. 470,806.

This invention relates to spring assemblies for upholstery and mattresses and more particularly to structures of this character commonly known as the type described and 5 claimed in the expired Marshall Patent No. 685,160 wherein each spring is completely and permanently confined in a tubular fabric housing closed at its ends, the several housings being joined at diametrically opposite sides to 10 form a continuous chain of the same.

In making up spring assemblies, a chain of these spring-filled housings is usually folded zig-zag upon itself to cover a given area corresponding substantially with that of the seat 15 cushion or mattress into which said springs are to be incorporated, the said chain of housings being generally suitably hand-stitched along their upper and lower surfaces to prevent unfolding thereof and crowd the housings together where required, and, after insertion of the spring assembly thus formed and insertion of the same into a cover fabric 20 lined with suitable padding, said assembly is further secured in place by means of tufting 25 and, in some instances, roll-edge stitching passing through peripheral corner portions of said assemblies.

The resulting structures have been generally satisfactory so that they have met with 30 great commercial success but have, in many instances, been found deficient in that one or several of the springs and cells containing the same have become turned out of vertical into canted or horizontal position and thus cause hollows to form in the surfaces of the mattresses or cushions and, furthermore, and particularly in mattresses, said springs and cells 35 tend to gradually crowd together and away from the boxing or peripheral walls of the cushion or mattress cover thus rendering the latter slack and causing the corner portions or roll-edges to sag.

To correct these defects, it is necessary to 40 remove the spring assembly and padding from the casing, stretch the assembly back to normal shape and readjust the position of displaced springs, all of which, including the evening up of padding, replacing the latter and said assembly in the cushion cover, etc., constitutes rebuilding of the structure at

a very appreciable expense, all of this being due to the fact that springs or housings containing them have not been adequately secured against relative movement and displacement in the assembly nor with respect 55 to the padding and cover fabric.

The main object of the present invention is to provide a spring assembly of the type specified wherein the springs and their housings are firmly held in proper relative positions 60 with relation to each other, the padding and the housing, so that a completed cushion or mattress containing the assembly will not suffer the defects above described.

Another object of the invention is to provide a spring assembly of the type specified wherein the several springs may be variously spaced and arranged relatively to each other and greatly varied in this respect from the conventional arrangement of said springs 65 and housings as now and heretofore generally practiced.

In the accompanying drawings illustrating the invention in several exemplary embodiments. 70

Fig. 1 is a top plan view, partly in section, of a spring assembly constructed in accordance with the invention.

Fig. 2 is a fragmentary vertical sectional view of the same. 75

Figs. 3 and 4 are views similar to Figs. 1 and 2, respectively, showing a modified form of construction.

Fig. 5 is a plan view, partly in section, of still another modified form of construction of 80 the assembly.

Figs. 6 and 7 are, respectively, a plan view partly in section, and a vertical longitudinal section of still another modified form of construction of the assembly. 85

Figs. 8 and 9 are fragmentary sectional views of the assembly illustrative of the method of making the same.

Fig. 10 is a view similar to Fig. 1 illustrating a further modification of the structure of the invention. 90

Fig. 11 is a fragmentary vertical sectional view illustrating a further modified form of construction. 100

Fig. 12 is a perspective sectional view of the same.

Fig. 13 is a fragmentary perspective view of a chain of spring-filled housings.

5 The structural characteristics of the spring assemblies of this invention will be most readily understood by first describing the method of making the same.

10 This consists in first laying two strips of fabric upon each other and joining them by stitch-chains extending transversely to the longitudinal edges of said strips in the well-known conventional manner, these initial steps not being herein illustrated. These 15 initial steps provide a series of flat housings or receptacles for springs and are open at both ends. It has, however, been customary in this art to fold a single strip of fabric upon itself midway of its longitudinal edges 20 to produce pockets or housings open only at one end, this form being advantageous in the instant case to produce certain types of assemblies as hereinafter fully described and may be used for all the several types of assemblies herein illustrated, though in the main, the pockets or housings open at both ends are better adapted to the purposes of this invention.

30 Having thus first completed a chain of said pockets or housings 1, preferably open at both ends, the first actual steps of the present invention are performed as follows:

35 A sheet 2 of a suitable fabric such as cheesecloth, muslin, cotton duck, or burlap, for example, is placed upon the table of a sewing machine. This sheet 2 preferably bears a series of parallel lines imprinted thereon, said lines being generally parallel with an edge of said sheet and constituting guide-lines.

40 A strip or chain of said pockets or housings 1 is now laid upon said sheet 2 so that one longitudinal edge portion thereof overlaps one of said guide-lines so that a stitch-chain 3 passed through said edge portion and said sheet 2 will serve both to close the pockets 1 of said strip at one end and will also firmly and permanently secure said strip to said sheet 2. It will be understood, of course, 45 that said edge portions of said chain or strip or, in other words, the mouth portions of the pockets or housings 1 thereof, will be gathered to the extent necessary to shorten them to correspond substantially with the diameter of the helical springs 4 which they are to contain.

50 This operation is repeated until the mouth portions of the pockets of each of a group of said strips or chains thereof have been secured to the sheet 2 by means of stitch-chains coincident with the said guide-lines.

55 The pockets 1 are still open at their other ends and as, in the majority of instances, the said pockets or housings 1 are interposed between the top and bottom fabric walls of a

cushion or mattress casing, it now becomes necessary to insert the springs 4 into said pockets or housings 1. This is done by first compressing the springs 4 and then inserting the same into the pockets 1 transversely of their ultimate and normal positions in the latter, the length of said springs being far greater than their diameters.

60 By thus positioning the springs 4 in said pockets or housings 1 as far as possible from the open ends of the latter, there will be ample slack fabric at said open ends to permit the mouth portions of said pockets to be secured by stitch-chains 5 to a second sheet 6 of fabric as shown in Fig. 9.

65 To effect this, the fabric sheet 2 is inverted, the fabric sheet 6, similarly provided with guide-lines, is then placed upon the sewing machine table and the fabric sheet 2 folded substantially as shown in Fig. 8 to permit stitching of an open end portion of each of the pockets 1 to said sheet 6 successively, thereby to close the open ends of said pockets or housings at the same time that they are secured to the sheet 6.

70 The spacing of the stitch-chains 3 and 5, respectively, may be equal to, slightly less, or appreciably greater than, a distance equal to the diameter of said springs 4 which, after the pockets or housings 1 containing the same have been secured to the sheet 6, are turned through an arc of ninety degrees to a position wherein their longitudinal axes are coincident with those of said pockets or housings 1 which they snugly fit and expand to 75 cylindrical form. The springs 4 are usually of greater length than the expanded pockets or housings 1 so that they remain slightly compressed and serve to form substantially flat circular fabric end walls for said pockets or housings 1.

80 It will be noted that in said drawings, I have shown layers 7 of suitable fibrous padding such as hair, cotton, sisal, for example, disposed upon the outer faces of said sheets 85 2 and 6 and have shown the stitch-chains 3 and 5 as extending through said layers 7 of padding, the latter being compressed by said stitch-chains. Thus the stitch-chains 3 and 5 serve also the third function of securing 90 padding layers 7 to the sheets 2 and 6.

95 In practice and for reasons hereinafter particularly set forth, the said padding layers 7 are first secured to the sheets 2 and 6 by means of parallel stitch-chains 8 extending transversely of the stitch-chains 3 and 5.

100 In the event of attachment of the pockets or housings 1 to the fabric sheets 2 and 6 only, as by omission of the padding layers 7, or in event of inclusion of the latter, the 105 springs 4 contained in said attached pockets or housings will be held in spaced relation to each other, especially with respect to preventing crowding together thereof beyond the extent to which the stiffness or tautness of 110

the fabric sheets 2 and 6 will so function. The layers of padding 7 obviously serve as a stiffening formation to resist crowding together of said springs. To prevent this crowding or to limit the same to the extent desired as in instances where the stitch-chains 3 and 5, respectively, are spaced from each other a distance slightly less than the diameter of the springs 4, the fabric sheets 2 and 10 6 and the padding layers 7 must be maintained stretched to a sufficiently taut condition. This is effected by means of the conventional border-frame 8^a, usually of fairly heavy wire, suitably secured to the peripheral edge portions of said sheets 2 and 6 and preferably, in the instant case, also secured to the padding layers 7. In most instances the said peripheral edge portions of said sheets 2 and 6 and said padding layers 7 are 15 of such width as to provide free portions 9 outwardly of the border-frames 8^a to provide what may be aptly termed boxing portions joined to form a peripheral wall about the spring assembly.

From the foregoing, it will be apparent that the spring assembly presents cooperating means whereby the springs are firmly and permanently maintained in predetermined relative positions from which they can not 20 be displaced otherwise than by partial destruction of the whole structure.

In instances where the padding layers 7 are used and the springs 4 closely grouped so that the pockets or housings 1 thereof are 25 all in surface contact with each other, the said border-frames 8^a may be omitted because said padding layers 7 are rendered sufficiently resistant by the compression along the stitch-chains extending transversely of 30 each other through the same and the resulting compression of padding thereby, to resist crowding together of said springs thus particularly adapting the assembly thus formed for incorporation into mattresses 35 wherein no border-frames may be used. Said padding layers are, however, sufficiently flexible to yield readily to surface pressures compressing certain groups of said springs so 40 that they are ideally adapted to the purposes 45 of the present invention.

The invention defined either in terms of method or of structure, permits of a wide range of relative position or grouping of springs which, insofar as I am informed, 50 has not heretofore been commercially possible with this general type of articulate spring-containing cell structure. A few exemplary relative arrangements of springs 55 and their housings are shown in the drawings, the heretofore conventional arrangement thereof being best illustrated in Fig. 5 wherein the springs of one strip are disposed 60 in staggered relation to those of the next adjacent strips this arrangement requiring the

maximum number of springs of a given diameter to cover a given area.

The relative arrangement of springs and their housings shown in Figs. 1 and 2 permits appreciably fewer but somewhat heavier 70 springs 4 to be used to produce an assembly equal in all respects to the conventional relative arrangement of said springs and can be produced at appreciably lower cost.

As shown in Figs. 3 and 4, the strips 10 of spring casings 11 may be constructed to cause said casings 11 to be spaced from each other by means of the parallel spaced stitch-chains 12 as shown, and said strips spaced from each other, said respective spacings 75 being such as to provide room for the un-housed springs 14 which are easily inserted after completion of the remainder of the assembly but before peripherally closing the same.

A further advantage of the invention resides in its adaptability to variation for the construction of seat cushions of various types as, for example, automobile seat-cushions which are high at the front and low at the rear, as shown in Figs. 6 and 7. For this type of structure the housings 15 of successive strips 16 are of successively decreasing depths and may be relatively arranged as shown in Figs. 1 or 3 or 5, or in any other 90 manner desired. In this type of cushion the base usually consists of a wire grid structure 16^a to which the bottoms of the pockets or housings are suitably secured in proper positions relatively to each other. In the manufacture of this type of cushion, it is preferable to form the articulate pocket or housing structure of a strip of fabric folded upon itself so that the resulting receptacles for the springs will be open at one end only and 95 will be closed at said ends after insertion of the springs by stitch-chains extending through the cover fabric of the assembly.

In the structures shown and described, the springs of the pockets or housings surrounding or adjoining any given one of the latter will, by reaction upon relief of load, elongate such one of said housings wherein the spring may have been displaced under the influence of the load and will thus cause said spring 110 to resume its normal position, this being due to the fact that the cover fabric of the assembly is so attached to each spring-housing as to cause the latter to be lifted as the cushion is relieved of load. By so relatively arranging the springs and housings as to avoid the crowding above referred to, each spring is afforded greater freedom of action and given room sufficient to permit it to resume its normal position besides providing access to 115 the hand to reach any displaced spring by merely opening up one side or end of the cushion casing.

It will be obvious that the action described in the next preceding paragraph is quite 120

different from that of the springs of the conventional type of assembly which is held in place in the outer casing by the tufting as above indicated.

- 5 A particularly advantageous relative arrangement of the springs and pockets is shown in Fig. 10 wherein the several articulate pockets or housings structures extend diagonally of the top and bottom wall structures thus eliminating the alternate unfilled spaces 17 of Fig. 5 adjacent the boxing of the structure while also permitting a very close or a spaced grouping or relative arrangement of the springs as desired, the 10 strips or chains of said spring pockets or housings of Fig. 10 being either of the type shown in Figs. 1 and 2, or the type shown in Figs. 3 and 4.

The term "stitch-chains," as used in this 20 specification, shall be construed to include hand or machine sewing or any other type of fastening means adapted to the purposes of the invention.

In practice, the spring assemblies are preferably made to include the padding layers. 25 These present rough outer faces having corrugations or biscuit formations, the surfaces of which present loose fibres and loose ends of fibres, all of which contribute to hold in place additional padding, such as short fibre cotton or the like, interposed between said padding and the cushion or mattress covers without resort to tufting. This additional padding obviously intertwines its fibres with 30 those of the padding layers of the assembly and is sufficiently compact to reinforce the said padding layers of the assembly to increase the normal resistance of the latter to contraction under the influence of pressures 35 against the peripheral walls or edges of the cushion or mattress and consequent crowding together of the springs thereof.

A further important modification of both 40 the structure and method of this invention is illustrated in Figs. 11, 12, and 13.

45 By reference to Letters Patent No. 1,733,660, and No. 1,566,068 and possibly others, it will be noted that the general practice in this particular art is to insert the 50 springs transversely of their normal positions into the open mouths of the chain-pockets formed by folding the fabric strip upon itself and inserting the cross-stitch-chains to form the pockets and then, after insertion of 55 said springs, to run a stitch-chain through the opposed walls of the mouth portions of said pockets to close the same, the first-mentioned patent contemplating the insertion of said springs and said last-mentioned stitching 60 as successive operations without necessitating removal of the chain-pockets from the position occupied during insertion of said springs.

The use of the folded strip of fabric to provide 65 chain pockets open at but one end and

the last-mentioned method of insertion of springs followed by closure of the mouths of said pockets effects economy of both material and labor and produces spring-filled chain pockets ready for further manipulation in accordance with the present invention.

70 When the springs are normally positioned in said pockets so that the latter are distended to cylindrical form with flat circular end walls, there remains slack fabric at diametrically opposite points of both end walls of said pockets or housings in alignment with the stitch-chains defining said pockets or housings.

75 In Figs. 11 and 12, the complete structure of the invention comprises a plurality of rows or chains of pockets or housings 17 defined by stitch-chains 18 and having their mouths closed by means of the stitch-chains 19. The slack fabric above-mentioned is indicated at 20 and is secured to the fabric sheet 21 by means, preferably, of a continuous stitch-chain 22 for each row or chain of pockets or housings 17 of the structure especially if the layer of padding material 23 is disposed 80 upon the outer face of the latter. The slack fabric portions 20 are present at both ends or tops and bottoms of the chain of spring-containing pockets or housings, the springs 24 of which are turned to normal positions after 85 the stitch-chains 22 have been passed through 90 said slack fabric portions 20 as described and shown.

95 The slack fabric 20 referred to is best shown in Fig. 13.

100 This attachment of the slack fabric portions 20 to the fabric sheet 21 either by means of the stitch-chains 22, or any other suitable securing means, is very advantageous for the reason that some or practically all of this 105 slack is taken up and the end coils of the springs 24 are thus more closely hugged by the fabric and are far less liable to become displaced than if said slack fabric is left free. Furthermore, the pockets or housings 17 are 110 just as firmly and durably held in proper relative positions with respect to each other and the fabric sheet as if the stitch-chains 22 extended through the mouth portions of the fabric to close the latter as illustrated in and 115 hereinbefore described with reference to Figs. 1 to 10, inclusive.

120 While the housings or pockets 17 shown in Figs. 11 and 12 are of the type closed by stitch-chains at both ends, I have, in Fig. 13, 125 illustrated the bag-type of pockets or housings made from a folded strip of fabric and open at only one end each, the initially closed or bottom ends of said pockets or housings being selected for most clearly illustrating 130 the slack fabric portions 20.

I claim as my invention:

1. A spring assembly comprising a series of continuous rows of spring containing fabric receptacles each open at one end, a fabric

- sheet, and a row of fastening means passed through opposed walls of the open end portions of said receptacles and through said sheet for simultaneously closing said open ends of said receptacles of each row and securing said rows of receptacles to said sheet in spaced relation to each other and means operatively engaged with said sheet for preventing gathering and bunching thereof to thereby maintain said rows of spring containing receptacles in said spaced relation to each other laterally and longitudinally of said rows. 6
2. A spring assembly comprising a layer of fibrous padding material, a plurality of spring containing fabric receptacles each open at one end, a sheet of textile fabric interposed between the open ends of said receptacles and said layer of padding, and means passing through opposed walls of the open end portions of said receptacles, the fabric sheet and the padding for simultaneously closing the open ends of said receptacles and securing the latter and said padding layer to said fabric sheet, said padding constituting means for preventing gathering and bunching of said sheet and thereby maintaining the said receptacles in said spaced relation to each other longitudinally and laterally of said sheet. 10
3. A spring assembly comprising a plurality of continuous rows of spring containing fabric receptacles open at both ends, a pair of fabric sheets between which said receptacles are interposed, and securing means passing through opposed walls of the respective open end portions of said receptacles and through the respective fabric sheets to simultaneously close the open ends of said receptacles and secure the same respectively to said respective fabric sheets, and means operatively secured to said respective fabric sheets for preventing bunching and gathering of the same to thereby maintain said receptacles in said spaced relation to each other laterally and longitudinally of said sheets. 15
4. A spring assembly comprising pairs of strips of textile fabric secured together by means of stitch-chains disposed in spaced relation to each other and extending transversely of the longitudinal edges of said strips and providing a series of rows of spring receptacles open at their ends, a pair of fabric sheets between which said receptacles are interposed, a spring in each of the latter, and rows of securing means extending transversely of said stitch-chains adjacent the respective longitudinal edges of said first-named fabric strips and through the said fabric sheets for simultaneously closing said receptacles and securing the same to said fabric sheets and means operatively secured to said respective fabric sheets for preventing bunching and gathering of the same to thereby maintain said receptacles in said spaced relation to each other laterally and longitudinally of said sheets. 20
5. A spring assembly comprising a plurality of pairs of textile fabric strips, the strips of each pair secured together by means of stitch-chains extending transversely of the longitudinal edges of said strips and spaced apart to provide rows of spring receptacles open at their ends, a pair of fabric sheets between which said rows of receptacles are interposed, a spring in each of said receptacles of each row, and parallel sets of stitch-chains passing through the pairs of fabric strips adjacent the respective longitudinal edges of the latter and through said respective fabric sheets in spaced relation to each other thereby simultaneously closing the ends of said receptacles to trap the contained springs and secure said rows of receptacles to said fabric sheets and means operatively secured to said respective fabric sheets for preventing bunching and gathering of the same to thereby maintain said receptacles in said spaced relation to each other laterally and longitudinally of said sheets. 25
6. A spring assembly including a fabric sheet, a layer of padding disposed upon one face of said sheet, parallel stitch chains securing said padding to said sheet, a series of fabric housings for springs each open at one end and disposed in predetermined relative positions on the other face of said sheet, and stitch-chains passing through said layer, said sheet and opposed walls of the open ends of said housings and laterally of the first mentioned stitch-chains for permanently joining said layer, sheet, and housings and closing the open ends of the latter also, and springs disposed in said housings, said padding and stitch-chains coacting to prevent gathering and bunching of said sheet and constituting means for maintaining said housings in said predetermined relative positions. 30
7. A spring assembly including a fabric sheet, a layer of padding disposed upon one face of said sheet, parallel stitch chains securing said padding to said sheet, a series of fabric housings for springs each open at one end and disposed in predetermined relative positions on the other face of said sheet, and tightly drawn stitch-chains passing through said layer, said sheet and opposed walls of the open ends of said housings and laterally of the first mentioned stitch-chains for permanently joining said layer, sheet, and housings and also closing the open ends of the latter, and compressing and stiffening said layer along said stitch-chains, and springs disposed in said housings, said padding and stitch-chains coacting to prevent gathering and bunching of said sheet and constituting means for maintaining said housings in said predetermined relative positions. 35
8. A spring assembly including a fabric

sheet, a layer of fibrous padding material secured to one face of said sheet by substantially parallel stitch-chains, a series of fabric housings for springs disposed upon the other face of said sheet in predetermined relative positions, and stitch-chains extending transversely to said first-mentioned stitch-chains through said padding, said sheet and end portions of the said housings for permanently closing the latter, compressing said layer along the last-mentioned stitch-chains and also securing said housings to said sheet, and springs in said housings, said padding and stitch-chains coacting to prevent gathering and bunching of said sheet and constituting means for maintaining said housings in said predetermined relative positions.

9. A spring assembly including initially flat fabric housings for springs closed along their side edges and ends, springs disposed in said housings and distending the same to substantially cylindrical form, said distended housings presenting substantially flat, circular end walls having bag-like slack portions at diametrically opposed points, a fabric sheet opposed to one end wall of each of said housings, and stitch-chains extending substantially diametrically of and through the fabric of said end walls opposed to said sheet and through said slack portions of said end walls and through said sheet for securing said housings to said sheet in predetermined positions relatively to each other, said stitch-chains taking up portions of said slack fabric to thereby more firmly confine the end coils of springs in said pockets against lateral movement relatively to the end walls of said pockets.

10. A spring assembly including initially flat fabric housings for springs closed along their side edges and ends and joined together to form chains of said housings, springs disposed in said housings and distending the same to substantially cylindrical form, said distended housings presenting substantially flat, circular end walls, free outwardly extending fabric flanges disposed diametrically of said end walls of said housings, a plurality of said chains of housings being disposed in spaced relation to each other, a fabric sheet opposed to one end of each of said housings, of said several chains thereof fastening means securing said fabric flanges to said sheet thereby to secure said housings to said sheet in predetermined relative positions, and means secured to said sheet and coacting with said stitch-chains to prevent gathering and bunching of said sheet and thereby maintaining said housings in said spaced relation to each other.

11. A spring assembly including spring-filled fabric pockets maintained normally distended longitudinally and circumferentially by the springs contained therein, said fabric pockets presenting bag-like slack fab-

ric portions at diametrically opposed points of each of their end walls, a sheet of textile fabric opposed to an end wall of each of said pockets, and means securing said slack fabric portions of the latter to said fabric sheet, said securing means taking up portions of said slack to thereby more firmly confine the end coils of springs against lateral movement relatively to the end walls of said housings.

12. A spring assembly including spring-filled fabric pockets maintained normally distended longitudinally and circumferentially by the springs contained therein, said fabric pockets presenting slack bag-like fabric portions at diametrically opposed points of each of their end walls, a layer of material opposed to an end wall of each of said pockets, and fastening means extending through said fabric sheet and said slack fabric portions of the opposed end walls of said pockets for securing the latter to said layer and take up portions of said slack to thereby more closely confine the end coils of the springs against lateral movement relatively to the end walls of said pockets.

13. A spring assembly including spring-filled fabric pockets maintained normally distended longitudinally and circumferentially by the springs contained therein, said fabric pockets presenting bag-like slack fabric portions at diametrically opposed points of each of their end walls, a layer of fibrous padding material disposed parallel with the plane of the end walls of said pockets, a sheet of textile fabric interposed between said padding and said pockets, and a stitch-chain passing through said padding, said sheet of fabric and said slack fabric portions of said pockets to secure the latter and said padding to said fabric sheet and take up portions of said slack to thereby more closely confine the end coils of said springs against lateral movement relatively to the end walls of said pockets.

14. A spring assembly including a plurality of rows of articulate distended cylindrical fabric housings having flat end walls, a spring in each housing of each row disposed in axially spaced relation to each other, said rows relatively arranged to axially space the springs of one row a predetermined distance from the springs of a contiguous row, a flexible plane element disposed parallel with the flat end walls of all housings of the several rows, rows of fastening means disposed substantially diametrically of the end-walls of all of the housings of the respective rows of the latter and securing the same to said flexible element, and means engaged with the latter to prevent gathering and bunching thereof and co-acting with said fastening means to maintain said housings of the several rows thereof and maintain said several rows of housings firmly in relative positions

corresponding with the axial spacing of the contained springs as aforesaid.

15. A spring assembly including a plurality of rows of articulate distended cylindrical fabric housings having flat end walls, a spring in each housing of each row disposed in axially spaced relation to each other, said rows relatively arranged in substantially parallel relation to each other to axially space the springs of one row a predetermined distance from the springs of a contiguous row, a flexible plane element disposed parallel with the flat end walls of all housings of the several rows, substantially parallel rows of fastening means disposed substantially diametrically of the end walls of all of the housings of the respective rows of the latter and securing the same to said flexible element, and means engaged with the latter to prevent gathering and bunching thereof and co-acting with said fastening means to maintain said housings of the several rows thereof and maintain said several rows of housings firmly in relative positions corresponding with 25 the axial spacing of the contained springs as aforesaid.

In testimony whereof, I have hereunto set my hand this 21st day of July, 1930.

LOUIS A. SUEKOFF.
